UNITED STATES PATENT OFFICE.

JOSEPH G. MOOMY, OF ERIE, PENNSYLVANIA.

RUBBER-WORKING APPARATUS.

1,255,456.

Specification of Letters Patent. Patented Feb. 5, 1918.

Application filed January 9, 1917. Serial No. 141,392.

To all whom it may concern:

Be it known that I, JOSEPH G. MOOMY, a citizen of the United States, residing at Erie, in the county of Erie and State of Pennsylvania, have invented new and useful Improvements in Rubber-Working Apparatus, of which the following is a specification.

This invention relates to rubber working apparatus and consists in certain improvements in the construction thereof as will be hereinafter fully described and pointed out in the claims.

The object of the invention is to reduce and simplify the labor involved in making certain rubber articles, particularly inner tubes for tires.

The invention is illustrated in the accompanying drawings as follows:

- 20 Figure 1 is an end view of the apparatus.
Fig. 2 a front view of the apparatus.
Fig. 3 a plan view.

In the making of tubes the rubber sheet is cut to length, rolled on a pole and the rubber on the pole then wrapped with a fabric so as to hold the rubber sheet while it is being vulcanized. Ordinarily the operation first involves the cleaning of the pole so as to obviate the marking or sticking of the rubber to it as it is vulcanized. In this apparatus, 1 marks the pole cleaning machine, 2 the cutting bench, 3 the tube rolling bench and 4 the pole wrapping machine. Heretofore the practice has been to separate these 30 different devices and do the different operations in considerable quantities at points not immediately adjacent.

The details of the pole cleaning machine form no part of this invention. It comprises 40 the head-piece 5 carried in the bearings 6. The head-piece is driven from a pulley 7 through a friction clutch 8. The friction clutch is normally held out of engagement by a spring 9 and is drawn into engagement 45 by the cables 10 operating from a foot lever 11. A tail-piece 12 is carried by bearings 13 and is forced forward by a spring 14. A pole 15 is engaged by the head-piece 5 and centered and held against the head-piece by 50 the tail-piece through the action of the spring 14. It is rotated rapidly and thoroughly cleaned. It will be understood that even finger marks on the pole will show on the finished tube so that the pole must be 55 carefully cleaned and handled with this in view.

After the pole is cleaned it should be carried to a point of easy access to the operators on the rolling bench 3. I accomplish this in a simple and convenient manner by 60 providing the ways 16 which are formed of pipe and extend across the benches 2 and 3 at a height just sufficient to clear the heads of the operators. These ways are supported by the uprights 17 and 18 arranged at the 65 rear sides of the benches. The ways are slightly inclined and provided with stops 19 which are locked with set screws 20 and may be adjusted along the ways as desired. The poles as they are cleaned are placed by 70 the operator of the cleaning machine on the ends of the ways. The pole then rolls down the way by gravity, the engagement of the pole with the two ways keeping it in parallel.

75 A sheet supply roll 21 is carried by the brackets 22 extending from the end of the cutting bench 2. The cutting surface 23 on the cutting bench, ordinarily formed of zinc or similar material is at a proper height to 80 receive the sheet from the roll 21. Scales 24 and 25 are arranged at the rear side of the bench 2. These scales are arranged in reverse relation, preferably with the zero points toward each other. As indicated the 85 scale 24 has marks one inch apart starting with one and ending with twelve, while the scale 24 has the marks seventy-two and extending up as far as desired. Two operators usually work in this cutting and rolling. 90 The sheet is pulled forward rapidly to some point opposite the scale 24. The operator at this end calls the point to the operator opposite the scale 25 and the operator at the scale 25 makes the proper deduction from 95 the desired length as indicated on the scale 25 and makes the cut. Thus if a sheet eighty inches is desired and the end opposite the scale 24 reaches the point six, indicating six inches beyond the zero point, the operator 100 opposite the scale 25 will cut at seventy-four. This obviates the nice placing of the sheet which by reason of its shape, length and character would require considerable time.

105 The sheet is then transferred to the rolling bench. The pole 15 is taken from the way 16 by lifting it and moving one end clear and then bringing it down between the ways. The tube is rolled in the usual 110 manner on the bench 3 and the tube so rolled is either passed directly to the operator on

the wrapping machine or is placed in the rack formed by the pins 26 on the uprights or supports 18, these racks being an easy reaching distance from the operators on the 5 rolling bench and to the operator handling the wrapping machine.

The wrapping machine has the head 27 mounted in bearings 28. It is driven from a pulley 29 through a friction clutch 30. 10 The friction clutch 30 is normally kept out of engagement by a spring 31 and is thrown into engagement by cables 32 (see dotted lines) operated by a foot treadle 33. A tail-piece 34 is carried by the bearings 35 15 and is forced forward by a spring 36. A bar 37 over which the muslin may be drawn is also usually supplied. The wrapping machine operates in the usual manner. The pole with the rubber sheet formed thereon 20 is engaged by the head and held in place by the tail-piece. It is rapidly rotated as the clutch is set and the muslin is wound spirally around the tube, the operator putting the muslin under tension as it is 25 wrapped.

The apparatus here described occupies very much less space than is usually taken up by an apparatus accomplishing the same purpose. There is no extra handling of 30 the poles or the parts and very little chance for the accumulation of dirt on the poles or injury to the tube formed on the poles before wrapping. A very considerable saving of time over usual methods is accomplished.

What I claim as new is:—

1. In a rubber-working apparatus, the combination of a cutting bench and a rolling bench with intervening spaces for operators; and pole-supporting ways above said benches at a height to clear the heads of the operators.

2. In a rubber-working apparatus, the combination of a pole-cleaning device; a 40 tube-forming bench in parallel with the pole-cleaning device; and pole-supporting ways above said device and bench at a

height to clear the head of an operator and extending to a position within reach of the operator of the pole-cleaning device. 50

3. In a rubber-working apparatus, the combination of a pole-cleaning device; a tube-forming bench adjacent to and parallel to the pole-cleaning device; a tube-wrapping machine parallel and adjacent to the tube-forming bench and at the opposite side of said bench from the pole-cleaning device; and pole-supporting ways above said device and bench at a height to clear the head of an operator and extending to position to be 60 reached by the operator of the pole-cleaning device.

4. In a rubber-working apparatus, the combination of a pole-cleaning machine; a sheet-cutting bench adjacent and parallel 65 to the pole-cleaning machine; a tube-rolling bench parallel to the sheet-cutting bench, said benches having intervening spaces between them for operators; a tube-wrapping machine adjacent to and parallel to the 70 tube-rolling bench; and pole-supporting ways above said benches at a height to clear the heads of the operators and extending to a position to be reached by the operator of the pole-cleaning machine. 75

5. In a rubber-working apparatus, the combination of a pole-cleaning machine; a sheet-cutting bench adjacent and parallel to the pole-cleaning machine; a tube-rolling bench parallel to the sheet-cutting bench, 80 said benches having intervening spaces between them for operators; a tube-wrapping machine adjacent to and parallel to the tube-rolling bench; and pole-supporting ways above said benches at a height to clear the 85 heads of the operators and extending to a position to be reached by the operator of the pole-cleaning machine, said ways being inclined to permit of the movement of the poles by rolling under the influence of 90 gravity.

In testimony whereof I have hereunto set my hand.

JOSEPH G. MOOMY.
